CLAIM

An ornamental design for a wearable breast pump as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a wearable breast pump in accordance with an embodiment of our new design that includes a lower container part and a breast contact part that are made of transparent or translucent materials;

FIG. 2 is a front elevational view of the wearable breast pump illustrated in FIG. 1;

FIG. 3 is a rear elevational view of the wearable breast pump illustrated in FIG. 1;

FIG. 4 is a left side elevational view of the wearable breast pump illustrated in FIG. 1;

FIG. 5 is a right side elevational view of the wearable breast pump illustrated in FIG. 1;

FIG. 6 is a top plan view of the wearable breast pump illustrated in FIG. 1; and,

FIG. 7 is a bottom plan view of the wearable breast pump illustrated in FIG. 1.

Color drawings have been submitted in this application. The color drawings are necessary as the only practical medium by which aspects of the claimed subject matter may be accurately conveyed. However, the color shown in the drawings is not part of the claimed design. In other words, the color shown on the claimed design forms no part of the claimed design.
